SUPPLEMENTARY GLAZING DEVICE FOR
GLAZED OPENINGS

Henry S. Conrow, Wichita, Kans.

Application July 10, 1934, Serial No. 734,543

6 Claims. (Cl. 20—56.5)

This invention relates to a device for the supplementary glazing of glazed openings. The object of this invention is to provide a device whereby a second or third glass may be added to a glazed opening with a dead air space between the panes of glass for the purpose of preventing heat losses, as there would be, through single panes of glass. This feature is not only desirable but necessary in rooms or buildings in which the air has been conditioned, that is, the air has been cleaned and cooled for summer, or cleaned and warmed for winter. Another object of my invention is to provide a device of the kind mentioned which can be applied to glazed openings that are already in use thereby changing the glazing from a single glass to a multiple glass, and doing so with a small cost and without loss of the sash or glass already in the building. A still further object is to provide a device of the kind mentioned which can be readily and easily attached to either wood or metal sash and the like. These and other objects will be more fully explained as this description progresses.

Now referring to the drawings in which the same characters of reference refer to the same parts throughout the several figures. Fig. 1 is a perspective and sectional detail through a wooden window frame and sash, parts being broken away for convenience of illustration. Fig. 2 is a perspective and sectional view of a portion of wooden sash to which a modified form of my invention has been applied. Fig. 3 is a perspective view of a portion of each of the elements employed in the supplementary glazing device. Fig. 4 is a detail perspective and sectional view of a steel frame and sash to which my invention has been applied. Fig. 5 is a perspective and sectional view of a wooden sash to which a modified form of my invention has been applied. Fig. 6 is a detail perspective and sectional view of my invention as applied for the complete multiple glazing as would be employed in refrigerator doors or windows and the like.

In the drawings, referring to Fig. 1, is shown the usual window frame 10, in which is mounted the upper sash 11 and the lower sash 12, each of which carries the usual pane of glass 13 and 14. The elements holding the second pane of glass 15 and 16 consist of a T shaped bar 17 and a channel shaped element 18. The channel shaped element 18 is made preferably of a spring material, such as spring brass. Between the element 17 and the sash is a sealing element such as a strip of felt or rubber 19 and in the elements 17 and 18 are holes 20 and 21 which register with each other

to receive screws or bolts for the purpose of holding the assembly together.

The assembly is made as follows: The sealing strip 19 is placed around the edge of the opening and may or may not be cemented to the sash, and over the sealing strip 19 and around the opening of the sash is placed the T shaped element 17 and within the space inclosed by the T shaped element 17 is placed the supplementary glass 15 or 16 which is embedded in putty or a mastic material and after the glass has been so set the channel element 18 is placed over the assembly just described in such a manner that one leg of the channel rests on the glass and the other leg rests on the outside portion of the T shaped element 17, then screws 23 are passed through holes 20 and 21 and screwed into the sash 11 or 12 so as to bind the glass 15 or 16 in an air tight joint between the elements 17 and 18 and also bind the elements 17 and 18 with an air tight joint between the element 17 and the sash on which the assembly is mounted. If the glass 15 is to be divided into small panes, a mullion frame carrying the small panes of glass is formed of the T bar 17' and the channel element 18' which are held together by bolts 24 which pass through the two members 17' and 18' and clamp on the glass 15, there being a putty or mastic material between the two elements 17' and 18' to form an air tight joint around the glass 15. The element 17' being attached preferably by being welded to the T shaped bar 17. In installing this supplementary glass mounting on a lower sash, the meeting rail of the sash would be rabbeted out as at 25 and a spring weatherstrip 26 would be attached to the meeting rail 27 on the upper sash and bear against the meeting rail 28 of the lower sash, to form an air tight joint between the two meeting rails as shown in Fig. 1.

It may be desirable at some time to make the supplementary glazing device so that it is not permanently attached to the sash, that is, it could be removed sufficiently to clean both sides of the glass without taking the device entirely off the sash, therefore, as shown in Fig. 2, the T shaped element 17 may be equipped with a hinge 29 which is attached to the sash 11 by means of screws 30, the hinge 29 being attached to the element 17 by being welded thereto or if desired, the hinge could be bolted to the T shaped element 17. In this construction the bolts 31 would be substituted for the screws 23 in Fig. 1, and the bolts would merely fasten the elements 17 and 18 together to clamp and hold the glass 15.

In Fig. 4 is illustrated my invention as being

5 applied to steel sash, the frame of which is designated at 32. 33 is the sash proper, holding the usual glass 13', and at 17 is the T shaped element and at 18 is the channel element, the two being held and clamped together by means of a bolt 34 which passes through the two elements 17 and 18 and is threaded into the steel sash 33. The glass 15' being mounted in a putty or mastic setting and being clamped between the elements 17 and 18 as 10 previously described.

10 In Fig. 5 is shown a multiple mounting of glass as applied to a wooden sash. This mounting comprises a T shaped element 17'', having an outwardly projecting shoulder 35 thereon against 15 which one leg of the channel element 18 may rest. At 15x is one of the supplementary glasses mounted in the T shaped element 17'' and being mounted in a bed of putty or mastic material and at 36 is an H shaped spacing bar resting against the leg of 20 the T shaped element 17'' and also against the glass 15x. At 15y is a second supplementary glass resting against the H shaped spacer element 36 and being mounted in a putty or mastic mounting as previously described. At 18 is the spring channel element resting against the glass 15x and the shoulder 35 and at 23x is shown screws passing through the elements 18 and 17'' and into the sash 11x and thereby rigidly binding the whole assembly together.

30 Now referring to Fig. 6, in this assembly is shown a multiple glazing comprising a channel element 37, having outwardly extending legs 38 which are attached by means of screws 39 to the face of an opening through a thick element such as a refrigerator door or the like and at 40, 41 and 42 are shown glass, the edges of which are fitted against the channel 37 and at 36' and 36'' are shown H shaped spacer elements between the panes of glass 40, 41 and 42. At 43 are shown the channel like elements, one leg of which rests against the glass 40 or 42 and the other leg resting against the sides of the channel 37. At 44 are bolts passing through the elements 11x and being threaded into the legs of the channel 37 and by turning the bolts 44 the channels 17x are drawn together and clamp against the glass 40 and 42 to make the rigid assembly as shown in Fig. 6.

50 It will be understood that the glass 40, 41 and 42 and the spacers 36' and 36'' are set in putty or mastic material to form an air tight joint between the several parts.

55 Such modifications may be employed as lie within the scope of the appended claims without departing from the spirit and intention of my invention. Now having fully described my inven-

tion, what I claim as new and desire to secure by Letters Patent is:

1. In a supplementary glazing device for glazed openings, said device comprising the combination of a frame element, the cross section of said frame element being substantially T shaped, glass in said frame, said glass resting on the T portion of said element, a channel like element, one leg of said channel like element resting against said glass, the other leg of said channel like element resting 10 against the opposite side of the T shaped frame element, a mastic material between said glass and said T shaped element and between said glass and said channel like element, and means for binding said T shaped element and said channel like element together to make a rigid mounting for said glass, and means for attaching the assembled framework to the frame of said opening.

2. A supplementary glazing device, said device comprising a T shaped element and a channel 20 shaped element, said channel straddling the stem of the T shaped element, a pane of glass intermediate one flange of the T shaped element and one leg of the channel, the other leg of said channel resting on the other flange of said T shaped element, said pane of glass being embedded in a mastic material held between said channel and said T shaped element, means for holding said channel and T shaped elements together, and means for attaching said elements to the frame 30 of a glazed opening.

3. A supplementary glazing device as in claim 2, and means for forming an air tight joint between said T shaped element and the frame element of said glazed opening.

35 4. A supplementary glazing device, said device comprising a frame work formed of a T shaped element and a channel like element, said channel like element straddling the stems of the T shaped element, and panes of glass intermediate the 40 flanges of said T shaped element and the legs of said channel like element, said panes of glass being embedded in a mastic material held between said T and channel shaped elements, and means for binding said T and channel shaped elements 45 together.

5. A supplementary glazing device as in claim 4, and means for attaching said device to the frame of a glazed opening and means to provide an air tight joint between said device and said frame of 50 a glazed opening.

6. A supplementary glazing device as in claim 4, and means for hingedly attaching said device to the frame of a glazed opening, and means for effecting an air tight joint between said device 55 and said frame of a glazed opening.

HENRY S. CONROW.
